Patented Apr. 8, 1913.

UNITED STATES PATENT OFFICE.

HYLA FREDERICK MAYNES, OF GAINES, PENNSYLVANIA.

AMUSEMENT DEVICE.

1,058,615.

Specification of Letters Patent.

Patented Apr. 8, 1913.

Application filed September 5, 1912. Serial No. 718,649.

To all whom it may concern:

Be it known that I, HYLA FREDERICK MAYNES, a citizen of the United States, and a resident of Gaines, in the county of Tioga and State of Pennsylvania, have invented a new and Improved Amusement Device, of which the following is a full, clear, and exact description.

The object of the invention is to provide 10 a new and improved amusement apparatus arranged to provide a highly exhilarating and rather unsuspected ride. For the purpose mentioned use is made of a slide and a starting chamber at the head of the slide, 15 the starting chamber having a collapsible support for a person to occupy, and means for collapsing the said seat in the direction of the slide to cause the person occupying the seat to slide down off the support and 20 down the slide.

A practicable embodiment of the invention is represented in the accompanying drawings forming a part of this specification, in which similar characters of reference indicate corresponding parts in all the 25 views.

Figure 1 is a perspective view of the amusement apparatus; Fig. 2 is a sectional side elevation of the chamber and the head 30 of the slide; Fig. 3 is a front elevation of the same, part of the exit door being broken out; Fig. 4 is a sectional plan view of the same on the line 4—4 of Fig. 3; Fig. 5 is a sectional side elevation of the same showing 35 the support collapsed, the floor of the chamber tilted and the exit door in open position; and Fig. 6 is a plan view of a modified form of the amusement apparatus.

At the head of a slide A of any approved 40 construction is arranged a chamber or housing B provided at one side with a door C and with a platform D supported on a suitable framework E a distance above the ground. The chamber B is provided with 45 a tiltable floor F by mounting the said floor on a transverse shaft F' journaled in suitable bearings in the sides of the chamber B. A seat G is arranged a distance above the floor F and is connected at its rear end by a 50 hinge G' to the back of the chamber B, and the front end of the seat G is connected by hinges G² with the upper end of a front leg G³ normally resting on the floor F in front of the shaft F'. On the top of the tiltable 55 floor F are arranged arms H adapted to engage the back of the seat G³ to swing the

same forwardly with a view to collapse the seat G and its leg G³ at the time the floor F is swung into a tilted position, as shown in Fig. 5. Springs G⁴ connecting the leg G³ 60 with the back of the chamber B may be used to normally hold the leg G³ in vertical position against the arms H, but the springs G⁴ may be omitted.

A pin I is arranged on one side of the 65 floor F near the front end thereof, and this pin I engage the slotted end J' of a link J pivotally connected with an arm J² secured on a transverse shaft K journaled in suitable bearings arranged on the front of the 70 chamber B. On the shaft K is secured the upper end of an exit door L for the front lower portion of the chamber B and which door L is normally in a vertical position and abuts against the front end of the tiltable floor F and projects slightly into the 75 upper end of the slide A, as plainly shown in Fig. 2. On the shaft K adjacent the entrance door C is arranged a handle K' under the control of the operator for turning the 80 shaft K with a view to swing the door L into an open position and to impart a tilting motion to the floor F.

Normally the floor F is held against tilting, and for this purpose the following arrangement is made: On the shaft K is secured an arm N connected by a link N' with an arm N² secured on a transverse shaft N³ extending through the rear of the chamber B below the seat G, as shown in the drawings, and the shaft N³ is journaled in suitable bearings attached to the back of the chamber B. On the said shaft N³ are secured arms N⁴ adapted to engage a catch O connected at its upper end by hinges O' to 90 the back of the chamber B. The lower end of the catch O is pressed on by a spring O² and normally extends over the rear end of the floor F so as to hold the said rear end of the floor against upward movement until 95 the shaft K is turned and a swinging motion is given to the arms N⁴ to move the catch O rearwardly out of engagement with the floor F thus releasing the latter.

The operation is as follows: When the 105 parts are in the normal position shown in Figs. 2, 3 and 4 and the door C is open then a person can pass readily through the open door into the chamber B to seat himself on the seat G with the feet resting on 110 the front end of the floor F. The operator now closes the door C and swings the handle

K' downward so that the catch O is swung rearwardly to release the floor F, at the same time the door L is swung upward, and when the slotted end J' engages with its upper end the pin I then a tilting movement is given to the floor F to swing the forward end downward into the position shown in Fig. 5, whereby the said floor F forms a continuation or extension of the bottom of the upper end or head of the slide A. The tilting movement given to the floor F causes the arms H to swing the leg G³ forward thus collapsing the seat G and the leg G³, whereby the said seat and leg assume an inclined position, as shown in Fig. 5, sufficient for the person seated on the seat G to slide off the latter and the leg G³ onto the forward end of the tilted floor F, onto the slide A, and down the same to the lower end thereof. It will be noticed that the person seated on the seat G is, as a rule, not aware of the collapsible support, the tilting floor, the door L and the slide A, and hence when the door L is opened the floor is tilted and the seat is collapsed so that rather an unsuspected ride is given to the person. After the person has started down the slide A, the operator swings the handle K' back into vertical position to close the door L to return the tiltable floor F to normal position and to release the catch O so that the latter moves back into holding position on the top of the rear end of the floor F. In a like manner the collapsed seat G and its leg G³ are returned to normal position by the action of the springs G⁴ so that the parts are ready for repeating the above-described performance with the next person. Inclined cleats G⁵ are preferably attached to the sides of the chamber B at the inside thereof to limit the downward swinging movement of the seat G, as will be readily understood by reference to the drawings.

In practice the seat G and its legs G³ extend the entire width inside of the chamber B so that the person is not liable to be injured when the seat and its leg are collapsed, as above described.

In the modified form shown in Fig. 6 a revoluble support P is provided at the upper end of the slide A at the platform D, and this revoluble support P is provided with four compartments each having a collapsible seat G, and a tiltable floor F, the same as above described in reference to the fixed chamber B. On revolving the support P the seats G and the floors F are specifically brought into alinement with the upper end of the slide A. The seat is then collapsed and the floor F is tilted to cause a person seated on the seat to slide down the slide A. The same means for tilting the floor F and collapsing the seat G is used as in the device illustrated in Figs. 1, 2, 3, 4 and 5, so that further description of the same is not

deemed necessary. It is understood that in this case a person passes from the platform D into the adjacent compartment and seats himself on the seat G, after which the support P is given a quarter turn so as to move this compartment in alinement with the slide A, after which the seat G is collapsed and the floor F is tilted to cause the person to slide down the slide A. While this takes place another person is seated in the compartment adjacent the platform D to be given a ride down the slide A on the next quarter turn given to the support P.

Having thus described my invention, I claim as new and desire to secure by Letters Patent:

1. An amusement apparatus, comprising a slide, a collapsible seat at the head of the slide, and means for collapsing the said seat to deliver a person seated on the said seat to the said slide while in sliding position. 85

2. An amusement apparatus, comprising a slide, a chamber at the head of the slide, a collapsible seat within the said chamber, and manually-controlled means for collapsing the said seat to form an extension of the slide and to deliver a person seated on the said seat to the slide and while in sliding position. 90

3. An amusement apparatus, comprising a slide, a chamber at the head of the slide and having an entrance and an exit in alinement with the slide, a collapsible seat within the said chamber and in alinement with the said exit and the said slide, and manually-controlled means for collapsing the said seat and opening the said exit to deliver a person seated on the said seat to the said slide. 95

4. An amusement apparatus, comprising a slide, a tiltable floor at the head of the slide and adapted to form a continuation thereof, a collapsible seat on the said floor and facing the said slide, and means for simultaneously tilting the said floor and collapsing the said seat. 105

5. An amusement apparatus, comprising a slide, a tiltable floor at the head of the slide and adapted to form a continuation thereof, a collapsible seat on the said floor and facing the said slide, a chamber inclosing the said floor and the said seat and having an entrance at one side, and a swing door at the front facing the said slide, and means for simultaneously tilting the said floor, collapsing the said seat and swinging the said door into open position. 115

6. An amusement apparatus, comprising a tiltable floor, a collapsible support having a seat and a leg, the seat being hinged at its rear end a distance above the said floor, 125 and the said leg being hinged to the front end of the said seat, and an arm on the said floor and adapted to engage the said leg to collapse the said support.

7. An amusement apparatus, comprising 130

a tilttable floor, a collapsible support having a seat and a leg, the seat being hinged at its rear end a distance above the said floor, and the said leg being hinged to the front end of 5 the said seat, an arm on the said floor and adapted to engage the said leg to collapse the said support, holding means to hold the said floor normally from tilting, and manually-controlled means for releasing the said holding 10 means and tilting the said floor.

8. An amusement apparatus, comprising a slide, a chamber at the head of the slide and having a tilttable floor, an entrance door at one side and an exit door at the front 15 facing the slide, a seat within the chamber and hinged at its rear end to the back of the chamber, a leg hinged to the front end of the seat and of the seat and adapted to normally rest on the said floor, and means for tilting the said 20 floor and collapsing the said seat and its leg.

9. An amusement apparatus, comprising a

slide, a chamber at the head of the slide and a tilttable floor, an entrance door at one side and an exit door at the front facing the slide, a seat within the chamber and hinged 25 at its rear end to the back of the chamber, a leg hinged to the front end of the seat and adapted to normally rest on the said floor, an arm on the said floor and adapted to engage the said seat leg, a catch adapted to 30 hold the said floor normally against tilting, and manually-controlled means connected with the said front door, the said floor and the said catch to open the door, to tilt the floor and to collapse the said seat and its leg. 35

In testimony whereof I have signed my name to this specification in the presence of two subscribing witnesses.
